BORDER FACER

Howard A. Smith, Dayton, Ohio

Application September 28, 1948, Serial No. 51,629

1 Claim. (Cl. 80—55)

1

The present invention deals with border facers of the type commonly employed to provide a perforated edge or border around a coupon or other element which is intended to be cut or torn from a newspaper, magazine, or comparable periodical.

At the present time it is common practice in the field of merchandising to include in advertisements a coupon which the customer is supposed to remove from the paper.

In order to facilitate this removal the edges of the coupon are defined by a broken line or a line having some design to it for indicating where the paper is to be cut or torn for removal of the coupon. These lines are impressed on the paper during the printing operation and ordinarily are created by forming shallow notches or teeth in the edge of a type bar which engages the paper. However, at the present time there is no practical method or machine for forming the notches in the edge of the type bar, the common practice being to use a saw or other comparable instrument which entails a laborious manual operation.

The present invention has in view as its foremost objective the provision of a new and improved method and apparatus for forming the notches in the edge of a type bar.

More in detail the invention has as an object the provision of an apparatus including a serrated or toothed wheel which is adapted to engage one end of a type bar, together with instrumentalities for causing the bar to be pressed against the wheel under pressure so that as the bar moves the wheel rotates and forms the notches desired.

Yet another object of the invention is the provision, in a border facer of the character indicated, of means for applying pressure to the bar as it passes over the serrated roll. This means is preferably located substantially opposite to the serrated wheel, so that the pressure created will be effective to a high degree.

Type bars of the character with which the present invention is concerned ordinarily are formed in a casting machine. It is believed that great advantages, from the practical viewpoint, can be achieved if the instrumentalities for forming the notches are mounted directly on a casting machine.

Thus, a further object of the invention lies in the provision of a casting machine of the type commonly employed to form type bars, together with means for forming notches in the edge of the bar, and which means is automatically operable as an incident to the operation of the casting machine.

2

Various other more detailed objects and advantages of the invention such as arise in connection with carrying out the above noted ideas in a practical embodiment will in part become apparent and in part be hereinafter stated as the description of the invention proceeds.

The invention therefore comprises a method and apparatus for forming notches in the edges of a type bar and which apparatus consists essentially of a serrated wheel, together with means for pressing a type bar thereagainst under pressure. The wheel and the pressure means may be included as a part of a type bar casting machine.

For a full and more complete understanding of the invention reference may be had to the following description and accompanying drawings wherein:

Figure 1 is a perspective view of a hand device which is made in accordance with the precepts of this invention;

Figure 2 is a vertical section taken about on a plane represented by the line 2—2 on Figure 1;

Figure 3 is an enlarged detailed perspective of the serrated roll;

Figure 4 is a top plan view of a modified form of roll;

Figure 5 is a similar view of another modified form of roll;

Figure 6 is a top plan view of the roll shown in Figure 3;

Figure 7 is a vertical section through a modified form of the manually operable device;

Figure 8 is a perspective of a portion of a casting machine and particularly that portion on which the notch forming device of this invention may be mounted;

Figure 9 is an enlarged perspective of a portion of the instrumentalities which are added to the casting machine; and

Figure 10 is a vertical section through the mounting for the serrated roller.

Referring now to the drawing, wherein like reference characters denote corresponding parts, and first more particularly to Figures 1 and 2, a manually operable hand device embodying the precepts of this invention is shown as comprising a main body member B, which is formed with a bottom 10, from which upstands side walls 11 and 12, which are arranged in spaced relation and which define a slot that is open at each end.

As is more clearly shown in Figure 2 the walls 11 and 12 are formed with openings 13 which are in alignment and which are lined with bearing sleeves 14. Trunnions 15 are journaled in these

bearings 14, and the trunnions 15 carry a serrated wheel designated 16.

The upper edge portion of the wall 11 carries an inwardly extending flange 17, which preferably is integral therewith, while the wall 12 is formed with a threaded passage. Substantially opposite to the flange 17 a screw 18 is threaded in this passage 18 and carries a plate 20 on its inner end.

The plate 20 is spaced from the flange 17 with the space between the two lying substantially midway of the roll 16. The outer end of the screw 18 carries an operating member in the form of a wing nut 21 which may be availed of to rotate the screw 18 and thus adjust the position of the plate 20.

The top face of each of the side walls 11 and 12 is formed with a plurality of threaded sockets 22.

A cover block 23 has its underface formed with a slot 24 which lies substantially opposite to the space between the flange 17 and plate 20.

This cover block is formed with a plurality of passages 25 which align with the sockets 22 in the upper faces of the side bars 11 and 12. As illustrated in the drawing, there are four of these passages 25 and, of course, a corresponding number of threaded sockets 22, one being located at each corner of the block 23. Obviously, this number may be varied as occasion demands.

Each of the passages 25 is enlarged to provide a counter-bore 26, and a bolt 27 having a head 28 is received in each of these counter-bores. Each bolt 27 passes through a passage 25 and has a threaded tip 29 that is screwed into one of the sockets 22.

An expansion coil spring 30 is mounted in each counter-bore 26 about one of the bolts 27. The upper end of each spring bears against the head 28 and the lower end against the bottom of the counter-bore. Obviously, these springs 30 will exhibit a tendency to urge the block 23 toward the main body B.

A pressure roll which is shown by the dotted lines in Figures 1 and 2 is designated 31 and is formed at each end with a trunnion 32 that is journaled in recesses in the body B. This pressure roll 31 bridges the slot 24 for a purpose now to be described.

A type bar is designated 33 and this bar has a lower edge 34 which is to be formed with notches or teeth. In forming these notches or teeth the bar 33 is passed between the serrated roll 16, and the pressure roll 24, the latter being mounted in the block 23, is urged downwardly by the influence of the springs 30 and thus exerts yielding pressure on the bar 33 as it passes over the serrated roll 16.

In order to insure that the bar 33 is properly held in an upright position, the plate 20 may be adjusted so that the space between this plate and the flange 17, which receives the bar 33, is of proper dimensions to accommodate the bar and at the same time maintain it in an upright position.

Referring now more particularly to Figures 3, 4, 5, and 6, it will be noted that the roll 16a, which appears in Figure 2, is illustrated more clearly in Figure 4. The surface of this roll carries what might be called cross serrations.

Another type of roll which is shown in Figure 5 may also be utilized. This roll is designated 16. It consists of nothing more than diagonal serrations on the cylindrical surface.

Still another modified form of serrated sur-

face is shown in Figures 3 and 6, in which the roll is designated 16b.

First modification

Figure 7 shows a form of device which is somewhat modified from that shown in Figures 1 and 2. It will be recalled that in the latter construction the entire cover block 23 is urged toward the main body member. In the form of the invention illustrated in Figure 7 the pressure roll 31 has its trunnions 32 received in slides 35 which are mounted for vertical movement in the cover block 23. Expansion coil springs 36 urge the slides downwardly and thus cause the pressure roll 31 to move against the upper edge of the type bar 33 under yielding pressure.

Second modification

A portion of a casting machine is illustrated in Figure 8. The casting machine is referred to in its entirety by the reference character C. It includes a pot 37 for receiving molten metal and a mold 38 which forms a type bar that emerges from the mold as represented at 39.

This bar now passes through a pair of guide blocks represented at 40, after which it may become subject to the instrumentalities provided in accordance with this invention.

The bed or frame of the casting machine is represented at 41. Mounted on this frame is a bracket 42 having an upstanding flange 43. Carried by the latter is a plate 44 which carries a serrated roll 45. The particular mounting of the latter will be later described in detail.

The bar 39 which is continuously formed in the mold 38 passes over the serrated roll 45 and is urged thereagainst under pressure by a roll 46 which engages the top edge of the bar. The latter is mounted on an arm 47 that is carried by the flange 43.

Upon referring to Figures 9 and 10, the particular mounting of the serrated roll 45 will be described. This serrated roll 45 is shown in the form of an annular ring which is positioned over a stud 48 and held thereon by a washer 49 and a screw 50. The stud 48 extends outwardly from a circular hub 51, and it is important to note that the axis of the stud 48 is eccentric with respect to the axis of the hub 51. The latter is rotatably received in a circular recess 52 formed in the plate 44 so that rotation of the hub 51 will vary the effective position of the serrated roll 45.

In order to accomplish this rotation of the hub 51 the latter is formed on its peripheral edge with a semi-circular groove 53 which is formed with threads. A screw 54 is screwed into a threaded bore in the plate 44 and which bore is represented by the broken lines at 55.

The bore 55 and screw 54 are tangentially disposed with respect to the hub 51. Thus the screw 54 meshes with the threads of the semi-circular groove 53. The exposed end of the screw 54 is slotted as shown at 56 which facilitates its rotation by a suitable tool, such as a screwdriver.

Thus, as the screw 54 is rotated the hub 51 is imparted a corresponding rotation to adjust the effective position of the serrated roll 45.

While preferred specific embodiments of the invention are hereinbefore set forth, it is to be clearly understood that the invention is not to be limited to the exact constructions, devices and mechanisms illustrated and described, because various modifications of these details may be provided in putting the invention into practice within the purview of the appended claim.

What is claimed is:

In a device for forming notches in the edge of a type bar, the combination of, a main block having upstanding side walls defining a central channel, a serrated roll journaled in said side walls and extending transversely of said channel, one of said side walls having an inwardly extending flange positioned above said roll, a plate within said slot adjustably supported by the other of said side walls for movement relative to said flange and disposed substantially in horizontal alignment with said flange, said plate and said flange defining a slot adapted to receive a type bar, a top block separable from said main block for relative movement therebetween and having depending side walls defining a central slot aligned longitudinally with said slot defined in said main block and having one wall thereof aligned vertically with said flange to cooperate therewith to support a type bar vertically within said slots defined in said main block and said top block, a pressure roll carried by said top block over said serrated roll with the axis thereof substantially parallel with the axis of said serrated

roll, guide means extending between said blocks for guided movement of said top block relative to said main block, and spring means engaging said top block yieldably urging the same toward said main block whereby to apply pressure upon a type bar placed between said rolls.

HOWARD A. SMITH.
